SEWING MACHINE

John P. Weis and Frederick F. Zeler, Nyack, N. Y.,
assignors to Willcox & Gibbs Sewing Machine
Company, New York, N. Y., a corporation of
New York

Application September 24, 1934, Serial No. 745,343

30 Claims. (Cl. 112—200)

The present invention relates to an improved sewing machine, and particularly to such a machine of the commercial type, capable of producing a wide variety of stitching operations economically.

Broadly stated, the present invention has for one of its main objects the provision of a single machine which may be made and used equally well as a sewing machine of the so-called flat bed or feed across the arm type, or as a sewing machine of cylindrical or feed around the arm type for hemming bloomers, step-ins, trousers, and overall legs, etc., and the provision of such a machine which may be made and used equally well as a longitudinal looper or as a transverse looper type machine, viz., changeable from needle loop taking and shedding travel in a direction transversely relative to the line of feed, to a direction longitudinally thereof, and for either single or multiple line stitching.

Complementary aims of this object are to provide a machine that has free access to the stitching instrumentalities for convenient threading, cleaning, and adjusting, whereby free space is provided for a large variety of attachments, readily adapting the machine to a wide variety of stitching requirements.

In the accomplishment of this object and the various aims, a machine has been developed with numerous advantageous features of construction, among which may be noted:

An improved lower or work supporting arm, which is sturdy and easily cleaned, including novel cloth plates and throat plates supported thereby, and which may be removed or changed one without the other; the cloth plates being of various sizes all supportable on the one lower arm to change the machine from a flat bed type to a cylindrical or feed around the arm type sewing, the arm having special supports so that it may be located and held with the head end projecting from a table to permit feeding around the arm; and the throat plates being provided with an underlying adaptor making possible the use of thin throat plates with thick cloth plates, independent removal of the plates, ample support for the thin throat plate while providing plenty of clearance for underlying loopers, and providing a novel support for a needle loop spreader. This advantageous lower arm also has the feature of supporting a novel needle guard.

Another feature of this improved lower arm is that, despite its interchangeable characteristics, it may be made as an integral part of the main frame, and despite its small size it may

be made very sturdy to withstand the stress and strain of operating multiple needles and loopers for gang stitching at high speed through thick, thin, and needle resistant materials. Further, this novel work supporting arm provides for the free passage of lint, grit, waste materials, and various substances that come from sewing, to prevent an accumulation of such materials interfering with the regular operation of the machine, means being provided so that such foreign matter may pass through or out of the way of working parts to avoid clogging.

In order to meet the above object, aims, and features, it has been necessary to devise special compact and highly efficient cooperating feeding, looper operating, needle operating, lubricating, and main driving mechanisms.

Thus, the invention has as another of its objects the provision of improved main driving mechanism for synchronously operating cooperating needle driving, loop forming, lubricating and work feeding mechanisms, which will be sturdily supported and well lubricated so that it will have a long life and freedom from repair.

Some of the aims in connection with this object are to provide a driving mechanism capable of operating at variable speeds, from minimum to maximum within the limits and possibilities that the sewing threads or the materials will endure (e. g., speeds of 5000 R. P. M. in the formation of stitches for the seams of garments and other sewed articles, in the placing of stitches for ruffling, tucking, shearing, gathering, and similar requirements, and in the formation of ornamental and decorative stitches) and to do this silently and smoothly at all speeds, with a minimum of vibration and maintenance cost.

Other aims in connection with this objective is to provide an improved operating mechanism with a minimum of inertia and one capable of quick acceleration, since considerable time may be lost in starting and stopping if the various operating parts are long or heavy, which may amount to considerable in a day's run of a machine that should be started and stopped between ten and fifteen thousand times in a working day of eight hours. Ease of control, or operation and the minimization of fatigue to the operator are of vital importance.

Several novel features have resulted from meeting this object and the complementary aims. One of these is the provision of a main frame with a hollow trunk adapted to locate and support substantially all the main driving mechanism, and which is open on three sides to facil-

tate initial assembly and adjustment and to make subsequent or field repairs and adjustments easier, but adapted to be closed later for thorough lubrication of all moving parts therein.

5 The main driving mechanism per se is particularly novel for it permits close spacing of the feed and looper parts in the under or work supporting arm which is desirable in order to feed small diameter cylindrical work therearound, and 10 because it is located substantially central relative to the needle, feeding, and loop forming mechanisms thereby minimizing inertia to increase the speed and performance of the machine. Another 15 advantageous aspect of the main driving mechanism is that one main crank shaft may be used equally well for driving of both transverse and longitudinal type loopers. By having the main drive shaft paralleling the other main operating rods of the looper and other cooperating mechanism, a minimum of driving interponents is required. The central location of the hand wheel adds to the convenience of operation for the operator, affording ease of operation, and eliminating the fatigue of reaching too far for positioning the needle, threading, stopping, and other 20 requirements of the hand wheel. Also, the central location of the main drive shaft permits the use of exceptionally short crank shafts and pitman connections to the various driven parts, 25 and thereby reduces inertia, vibration, and noise.

It is a further object of the present invention to provide a single sewing machine capable of making a variety of different forms of stitches, including ornamental as well as plain stitching.

30 Some of the complementary aims in connection with this object are to provide a machine which may be readily converted from single to a gang needle stitching operation with the looper or loopers either in line with or opposed to the line 35 of feed of the work. Also, aims in the accomplishment of this object are to provide such a mechanism, which, even though it is capable of making a variety and multiplicity of ornamental and plain stitching, will be simple, sturdy, easy to 40 assemble and to adjust, and capable of high speed 45 operation.

The mechanism meeting this object and aims of the present invention includes several very advantageous features among which the following should be particularly noted.

50 By having a single machine convertible for various stitching requirements, it is possible to have only one machine in place of several, thus reducing the initial financial investment, and 55 greatly reducing the amount of floor and table space required.

A form of interchangeable looper operating 60 mechanism which is sturdy and compact and which does not require large clearances or special supports in the lower arm, thereby making possible a compact and sturdy lower arm structure. Also, the mechanism is such that it is 65 possible to use the one frame and, in some forms of the invention, practically like parts for either a longitudinal or a transverse looper type mechanism to facilitate factory manufacture, storage of parts, and assembly, or in one form of the invention to use completely like parts for both longitudinal and transverse looper mechanism, whereby the machine by a simple and quick adjustment 70 may be quickly changed from one to the other.

This improved looper mechanism of the present invention in addition to supporting and operating single longitudinal and transverse loopers,

also conveniently supports and efficiently operates multiple or gang loopers of either type.

Yet another object of the present invention is to provide an improved needle loop spreader. In accomplishing this object a very efficient loop spreader has been provided which is advantageously supported and operated close to the top of the throat plate and which is operated directly by the looper drive shaft close to the needle and looper so that close operating relationship may 10 be maintained.

It is another object to provide an advantageous needle operating mechanism which will cooperate with the novel and efficient looper mechanism of the present invention to form improved 15 quality stitching.

A feature of the needle operating mechanism is the driving connections between the needle operating rod, the needle bar, and particularly the main drive shaft which insure a smooth driving action with very little inertia, when driven by a main drive shaft located substantially midway vertically in the trunk of the frame.

An improved feed, cooperating with the improved needle and looper operating mechanisms 25 of the present invention to form improved quality stitching, is a further object of the present invention.

Aims in connection with this object are to provide a feeding mechanism capable of accommodating and operating a wide variety of feed dogs and presser feet for single and multiple needle stitching operations, whereby a narrow feed for fine silks and the like and a single needle may be provided, or a wide feed of 3" or more 30 may be readily provided and employed for multiple needle stitching or for the powerful feeding necessary for the stitching of heavy materials, 35 side wall mattresses and the like.

In accomplishing this object several novel features have been provided by the present invention including a smooth operating mechanism between the main drive shaft and a feed rock rod, a semiclosed section of the main frame which may be easily opened and accessible supports to facilitate changing feed dogs, and a pointer co-operating with a graduated transparent indicator plate to quickly, clearly, and accurately indicate the number of stitches per inch.

The advantageous feature of interchangeability of wide and narrow feed dogs is accomplished 50 through the convenient centrally located hand wheel which permits easily and quickly shifting the feed dog carrier to the most accessible location, by easily removed interchangeable throat plates, and by the double open sided chamber 55 provided when the throat plate is removed.

A final object of the present invention is to provide an improved lubricating system for sewing machines and particularly a system which 60 will automatically and advantageously lubricate the novel feeding, looper, main drive, and other operating mechanisms of the present invention. Accomplished aims in connection with this object include having the operating mechanisms 65 enclosed to better control lubrication for all the operating parts, to avoid exterior oil holes, to make possible the reuse of oil for economy, and to prevent escape thereof from the machine to the articles being stitched or onto clothing of 70 the operator.

Advantageous features resulting from the accomplishment of this object include the provision of a transparent plate adapted to indicate whether oil is being pumped properly, and an- 75

other transparent plate adapted to indicate the amount of oil in the machine and what should be proper level of oil, both of said plates forming walls to the main frame to complete a closed chamber. Another feature is the provision of a mechanism adapted to advantageously direct oil by gravity, spray, and capillary principle or by combinations thereof to all the main operating mechanisms contained within the main frame. 10 Also, novel guiding means are provided for directing oil to particular locations.

Other objects, features, and advantages will appear hereinafter.

Figure 1 is a front view of the sewing machine 15 of the present invention with a section of the trunk end and the underarm broken away to show the main operating parts.

Fig. 2 is a view similar to Fig. 1 but gives a complete longitudinal sectional showing of the 20 present invention, of the transverse looper type.

Fig. 32 is a front view similar to Figs. 16 and 20, of the completely universal looper mechanism, in transverse looping position.

Fig. 33 is a front view similar to Fig. 32, but shows the universal looper mechanism in the longitudinal looping position.

Fig. 34 is a front view of the main driving mechanism for the universal looper mechanism.

Fig. 35 is a side view of the driving mechanism shown in Fig. 34.

Figs. 36 and 37 are fragmentary details of the universal looper.

Figs. 38 and 39 are similar to Figs. 32 and 33 35 but show a modified form of looper carrier.

The detailed description which follows, to facilitate a quick understanding of the machine and its operations, is broken down into various sections. The present invention is not limited to the details of construction and arrangement 40 of parts illustrated in the accompanying drawings for it is capable of other embodiments and the phraseology employed is for the purpose of description and not of limitation.

Frame and general structure

Referring now in detail to the drawings particularly to the general structure illustrated in Figs. 1 through 14, and particularly the transverse looper type shown in Figs. 2 through 9, the 50 present invention provides a frame 40 having many novel features, comprising a hollow trunk 41 for supporting a main driving mechanism 42, with a preferably hollow and integral upper arm 43 for supporting a needle operating mechanism 55 44 and a preferably integral lower arm 45 for supporting looper and feeding mechanisms 46 and 47 respectively and for forming a work support 48. In general it has a smooth outer finish for 60 appearance, ease in cleaning, and elimination of all outward obstructions which would interfere with handling of the work.

The frame 40 is near its center provided with a single foot 49 and the trunk end of the machine is provided with integral cooperating feet 49a and 65 49b to form a three point support. These three feet are spaced and located to provide proper means for fastening the machine to the table or any other suitable support in a manner to minimize vibration and to prevent distortion of 70 the frame and consequent binding and adverse wear on the various bearings. The feet may be provided with tapped holes 58 to receive the threaded end of bolts passed upwardly through a table or other support, or may be provided with 75

a hole or slot 50' to receive lag screws or bolts when the latter are passed to the support from the top.

The hollowed trunk 41 comprises a front wall 51, rear wall 52 and side walls 53 and 54, the latter having large side openings 55 and 56 respectively to accommodate and support the main driving mechanism 42. Further, the trunk is provided with a top opening 57 and a bottom opening 58 large enough to pass various operating parts and to receive the hands of a person making the original assembly or subsequent repairs and adjustments. A cover plate 59 and a bottom plate 60 are provided for the top and bottom openings 57 and 58 respectively, and are held in place with screws 59 and 60' in the usual manner. End caps 61 and 62 are similarly held against the side walls 53 and 54 respectively by screws 61' and 62' to make a complete oil tight closure for the main operating parts. These openings and caps permit bench assembly of all the operating parts contained in the trunk of a machine and facilitate assembly thereof by making it possible to pass the main driving mechanism 42 or large sub-units thereof through the various openings. When the caps are secured thereto an effective seal is provided which prevents leakage of oil while the machine is in operation.

In addition, thereto, the chamber 41' forms a reservoir for oil 63 as indicated in Figs. 2 and 6, and the chambered trunk 41 forms a support for an oil pump 404 and has transparent plates 65 and 66 to indicate both flow and quantity of oil 63, with the latter plate indicating operating characteristics of the feed mechanism 47 associated with the main drive mechanism 42 in the hollow trunk, all as described in detail hereinafter. The trunk is of suitable design for rigidity, of sufficient size to hold a supply of lubricant to last for a long period of time, and has sufficient space for air to dissipate heat of the oil and thereby prevent objectional oil vapors. The bottom cover plate 60 is provided with a valve 67 to drain oil 63 from the reservoir when the level is too high, when it is desired to change the oil, or for other like reasons.

The upper arm 43 is preferably made with a substantially hollow chamber 43' of substantially 50 rectangular and tapering cross section, and with a transverse web 68 at the trunk end, and a similar transverse web 69 at a head 70, at the end of the arm, to support a main rock shaft 71 of the needle operating mechanism 44. The head is provided with suitable bearings 72 and 73 for a needle bar 74 and a presser bar 75, see Figs. 2 and 5, and is provided with a large opening 76 to facilitate adjustments and repairs to the parts therein. This opening is normally 60 closed with a cover plate 77, held in place by screws 77', to cover up the working mechanism and to prevent adverse escape of oil.

The lower arm 45 is preferably made integral with the frame 40, with a front wall 78 and a rear wall 79 extending horizontally from the trunk in a direction parallel to and underlying the upper arm 43. In order to make these walls rigid or sturdy at the outer extremities, and in order to provide suitable bearings for important operating parts, an end wall 80 is provided at their outer extremities and a shorter transverse web 81 is provided intermediate the end wall 80 and the sides of the walls 78, 79, and 53.

The lower arm is provided with openings 82 and 83 between the walls 78 and 79 for con-

venience in assembling the machine to a bench, but primarily in order to facilitate cleaning lint, waste cloth materials, dirt, etc., by allowing them to pass on through so as not to interfere with working parts. The lower arm 45 provides a 5 sturdy non-vibrating support for both the feed mechanism 47 and the looper mechanism 46, detailed description of which is given hereinafter, but in addition forms a novel work support 48 for advantageously and interchangeably supporting variously shaped throat plates 84, cloth plates 85, and other instrumentalities so that the machine may in effect be changed from a flat bed type to a cylindrical type sewing machine and to facilitate making changes in the final stitch 15 forming instrumentalities in order to form divers type stitches, as will now be described in detail.

Work support

According to the present invention the lower 20 arm 45 and mechanism associated therewith are devised to provide a work support of short height and width, and to provide a sturdy and quickly interchangeable support for the throat plate 84. Supporting lugs 78a, 78b, and 78c, best seen in 25 Fig. 4, are provided on the front wall 78 and associated rear lugs 79a, 79b, and 79c are provided on the rear wall 79 to form a support for the long and large area cloth plate 85, which may be secured thereto by screws 86 entering tapped 30 holes 86'.

Preferably this plate is made of substantial width transversely of the lower arm as shown by solid lines in Fig. 3 to form a so called flat bed type machine. However, these lugs may support a narrow and small area cloth plate 85' shown in Fig. 3a. The underlying sections of the narrow plate 85' are the same as in the wide plate 85. As indicated by dot and dash lines in Fig. 3, when the narrow plate 85' is positioned 40 on the lugs there is formed a cylindrical type machine in which the work may be fed completely around the lower arm 45 when the frame 40 is secured to a table with the portion thereof beyond the foot 49 extending beyond the edge 45 of the table. This is a very real advantage in many industries for it makes possible an immediate change over in the same machine from a flat bed to a cylindrical type sewing machine 50 and results in considerable savings in equipment and floor space requirements. Thus, too, it will be apparent that the change over just described makes it possible to reduce the size of the lower arm almost in half.

The cloth plates 85 and 85' are normally made 55 of thick material for strength and rigidity and are provided with a cut-out 84', through its thickness, adapted to merely locate and not to support an adaptor 87 and the throat plate 84.

As may best be seen in Figs. 1 through 4, and 60 Figs. 11 and 13, the lugs 78a, 78b, 79a, and 79b are adapted to directly support the adaptor 87 and the throat plate 84, the latter being secured to the adaptor by screws 88 threaded into holes 88'. Interchangeable throat plates may be provided with various cut-outs to accommodate various stitching combinations, and also different widths of needle gauges for light and heavy work. The main purpose of the adaptor 87 is to make possible the use of a thick cloth plate 85 with 70 relatively thin throat plates, both resting upon the same bosses and more particularly to form a clearance for loopers 89, and a feed dog 90, see Figs. 2, 5, and 11, and a chamber 91 for a needle looper spreader 106 close to the point of stitch 75

formation in the material, such closeness being very desirable.

It also forms a rigid support for the throat plate to prevent deflection under heavy pressure from the needle when operating on heavy materials, and prevents deflection under heavy pressure of the presser foot. In addition, this arrangement of parts is such that the change over from the wide cloth plate 85 to the narrow cloth plate 85', and in effect the change from a flat bed to a cylindrical machine, may be effected without disturbing the throat plate which is desirable when there is a critical adjustment between the throat plate, feed dog, and the needle guide. Also, it is possible to remove or change the throat plate 84, without disturbing the cloth plate, when it is desired to make repairs, changes, or adjustments to the feed dog or looper forming instrumentalities located in the lower arm 45.

In addition this novel shaped work support 48 provided by the present invention furnishes an advantageous needle guard 94, see Figs. 12 and 13, adapted to guide or support a single needle 95 near the bottom of its travel, and to prevent the needle from being twisted or bowed by heavy materials or excessive pulling on the stitched materials while down, and particularly to align and maintain in alignment a plurality of needles, thereby insuring a more positive and efficient high speed operation of the machine and insuring high quality stitch formation. This needle guard mechanism as at present preferred is best illustrated in Figs. 12 and 13 particularly, and comprise a gate 96 pivotally mounted on a stud 97 threaded into a hole 97' in the end wall 80 so that it may be moved to an inoperative position shown by dot and dash lines 96', but which is normally supported in the operative position shown by full lines in Fig. 12 with the outer or free end thereof riding or resting upon a long stud 98, and stopped in the operative position by engaging an end of an adjustable stud 99 threaded into the lug 79b and locked in adjusted position by a nut 99'.

Normally the gate 96 is urged out to an inoperative position by a spring 100 so that the gate will not be half open or slightly open which would break loopers and needles. By urging it to the open position, operator can more easily thread loopers. The gate is locked in the operative position by a spring latch 101 engaging the rear end thereof. Preferably this latch is provided with a bevel 102 so that it need not be pushed back manually when the gate is moved from the inoperative to the operative position. The position of the needle at the lower end of its stroke relative to the guard 94 is clearly shown in Figs. 12 and 13. Multiple needles would, of course, be similarly located in any desired spaced relation lengthwise of the gate. The gate itself may be made of one piece construction and hardened to prevent wear from the needle; however, it is preferably provided with a hardened angular or like plate 103 held onto the top of the gate by two screws 104 passed through suitable elongated apertures 105 and threaded into the gate proper so that minor adjustments and movement to compensate for wear can be made with comparative ease and so that replacements of the worn needle engaging surfaces may be easily and cheaply made. The guard 94 or the plate 103 thereon may be provided with holes 94a or notches 94b to guide needles.

In order to move the needle guard gate 96 to the inoperative position, it is merely necessary to

push against the finger 101' Fig. 14a until the end of the gate is clear. The front wall 78 is provided with a cut out 78' which enables an operator to reach in with his fingers to manipulate the gate. However, fine adjustments of the guard 94 relative to the needle 95, or adjustment of multiple needles relative to the guard may be accomplished best by removal of the throat plate 84 and adaptor plate 87.

This throat plate 84 and adaptor 87 also provide a novel support for a needle loop spreader 106 comprising a channel 107 in the under side of the cloth plate adapted to receive a slide 108' having a hook 108 adapted to catch the needle thread. It is reciprocated in this channel by the looper mechanism through a connection 109. The throat plate and adaptor form a very satisfactory working support for the loop spreader slide close to the materials which is very desirable.

The novel lower arm 45, interchangeable work supports 48, the ready interchangeability of the throat plates 84 without changing the cloth plate 85 or 85', and the novel needle guard 94 form the subject matter of a continuation in part application Serial No. 750,259, filed October 27, 1934. Detailed, rather than brief description has been given herein in order to facilitate the description and a proper understanding of the novel looper mechanisms 46 and main driving mechanism 42, which have in part at least been developed to make possible the interchangeable flat bed and cylindrical machine of the present invention, and which form the main subject matter and claims of the present patent application.

Driving mechanism

A particularly novel part of the present invention is the main driving mechanism 42, the novel mounting therefor, and especially the arrangement thereof substantially midway between the needle operating mechanism 44 in the upper arm 43 and the feed and looper mechanisms 47 and 46 respectively in the lower arm with the axis thereof of substantially paralleling said needle, looper, and feed mechanisms.

This main drive mechanism may best be described in connection with the transverse looper, illustrated in Figs. 2 through 10 and 15 through 18. It comprises a main drive shaft 110 with cranks A, B, C, D, and E, preferably formed in the shape of a ball, accommodating main driving connections 42' including crank arms 111, 112, 113, 114, and 209 respectively, provided with ball socket connections 116, 117, 118, 119, and 120 respectively, (see Fig. 17) each including an arm cap 121 adapted to be threaded onto screw threads 122 on the individual crank arms and locked in the desired position thereon by nuts 123 and each provided with a top cap 124 secured to the arm caps by screws 125, in order to allow the crank arms to rotate relative to the balls and to permit slight vertical displacement for operating travel to compensate for slight irregularities in the location of those parts which connect with and are operated by the other end of the crank arms. Integral plates 126 reinforce the main drive shaft and, between the individual balls, may help to prevent the ball sockets from turning sidewise into the path of each other.

The crank arms 111 through 114 and 209 are preferably provided with a ball and socket and like connections 127, 128, 129, 130, and 131 respectively for connection to an arm 132, bell crank 133, arms 134 and 135, and link 207 at the ends 75.

opposite the main drive shaft 110 for operating the needle and other mechanisms all in a manner about to be described.

Except for a modified form of bell crank 133, shorter crank arm 113 and associated arm 134, see Figs. 1, 11, 21 and 22, the driving mechanism so far described applies for the longitudinal looper form of the invention shown in Figs. 1 and 11 particularly.

Before entering into a description of the various mechanisms operated by the crank arms, it should be noted that the main drive shaft 110 together with the main driving connections 42 including the crank arms and associated ball and socket connections, bell cranks, and arms just described may be assembled extraneously of the frame and may then be passed through the side wall opening into the chamber 41 of the hollow trunk 41 for assembly. These assembled parts, just described in detail, are tilted slightly and the crank arms are moved into the chamber whereupon the main shaft may again be moved into a horizontal plane substantially central of the side wall openings 55 and 56. An inside ball bearing 137 is moved through the side wall opening 55 while the inner end 110a of the drive shaft 110 is moved therein in the side wall openings and the outer end 110b of the shaft is, through a ball bearing 138 and the end cap 62, secured to the side wall 54. The bearing 138 is secured to the end cap by a shoulder and flange connection 139. The other end cap 61 is secured in place by screws 61.

A main drive pulley 140 is secured to the end 110b of the shaft 110 by a set screw 141 and a handwheel 142 may be made integral therewith or may, as shown, be secured to a shoulder 143 of the pulley with one or more screws 144. A thin washer between the bearing 138 and pulley 140 prevents excessive escape of oil through the ball bearing, and a drain 145 in the end cap 62 further collects and directs oil seepage from the bearing back into the chamber 41. By securing the inner race of the ball bearing 138 to the cap 62 between a flange 110c and the pulley 140, and by securing the outer race thereof to the end cap 62 as just described, the main crank is held substantially against endwise movement in the frame. This end-wise movement may be further controlled by properly locating and holding the other ball bearing 137 in any conventional manner in the side wall opening 55 in relation to a flange 146 on the main drive shaft 110. A retainer ring 148 in the bearing 137 and the end cap 61 prevents excessive leakage at this point.

This centrally located main drive shaft 110 brings the handwheel 142 into a location where it may be very conveniently grasped without danger of skinning knuckles as occurs sometimes when the handwheel is close to the base of the machine, and awkward twisting of the arm is required when the hand wheel is on the front of the machine. Further, and of particular importance, it makes possible the use of short crank arms to the various mechanisms, thereby overcoming vibration and inertia of moving parts to a very marked extent. This latter factor is enhanced by having the main drive shaft parallel the rocking and reciprocating rods of the various associated mechanisms. All of these advantages will be more apparent after the individual mechanisms are described.

However, it should be particularly noted that the centrally disposed maindrive shaft 110 is advantageously provided with a connection 149

on the end 110a indicated in Fig. 2, preferably in the form of a main shaft extension 149', including a threaded stud 150, projecting through a suitable aperture in the end cap 61. This connection thus provides a very convenient driver for pinking, and other devices secured to the cloth plate 85, for example, in tapped holes 151 or secured to the side wall 53, or bottom wall of the upper arm 43 for advantageous cooperation with the feed, looper, and needle operating mechanisms. This connection and auxiliary drive is described in much greater detail and separately claimed in a divisional application Serial No. 2806, filed January 21, 1935, and is referred to herein only to more clearly bring out the operating requirements and advantages of the main driving mechanism.

The main driving mechanism just described is, in its essential details, equally applicable for the operation of what is known in the art as a line 23 of feed or (longitudinal) looper, and for what is known as transverse looper type mechanisms, with only slight changes or adjustments required in the parts as described in detail hereinafter. However, the needle operating mechanism 44 driven 25 by the main drive shaft 110 through the crank A and crank arm 111 is the same for both types and will therefore be described in detail before describing the longitudinal and transverse looper mechanisms.

Needle driving mechanism

The needle driving mechanism 44 comprises the rocker rod 71 journaled in bearings 152 and 153 in the walls 68 and 70 respectively with an 35 arm 132 secured to the trunk end thereof by a yoke 154 and screw 155 and having a bearing stud 156 at its outer end connecting with the ball socket 121 at the upper end of the crank arm 111. At the head 69 on the end of the arm 43 the 40 rocker rod 71 is provided with a needle driving arm 157 adjustably secured thereto by two screws 158 for adjusting the height of the needle 95 relative to the looper. This arm is connected to a hollow needle bar 74 through a double link 159 45 having a link pin connection 160 to the arm 157 and having a similar link pin connection 161 to the stud 162 having a thread and lock nut connection 163 to the upper end of the needle bar 74 (see Fig. 5). At its lower end the needle bar is 50 provided with a chuck 164 adapted to interchangeably receive various types of needles 95 in the conventional manner.

As may be seen best in Figs. 1, 3, 5, and 11, the stud 162 is provided with a finger 165 extending through an opening 166 at the front of the head, and exteriorly of the latter is provided with a thread carrying eyelet 167 secured thereto by a screw 168. This finger is in the form of a slide adapted to ride between plates 169 secured to the 60 head 69 in spaced relation by screws 170. This latter structure insures a sturdy driving action between the arm 157 and the needle bar 74 and also insures an efficient drive for the thread carrying eyelet 167 which forms a slack for the formation of succeeding stitches. One vertical reciprocation of the needle downward and upward by the crank arm 111 is accomplished each time the crank A on the main drive shaft is given a complete revolution.

The feeding mechanism

The feeding mechanism 47 for moving materials through the machine of the present invention for either longitudinal or transverse looper 75

type stitching, is the same. It comprises a feed rock rod 171 and a feed lift rod 172 mounted in suitable bearings in the lower arm 45 and trunk 41. This mechanism is best seen in Figs. 4 through 11. It comprises a feed dog 173 secured to a feed dog carrier 174 as by screws 175, and this carrier in turn is connected to an arm 176 adjustably clamped to the rock shaft 171 by the split clamp construction 177 through a spring 178 under screws 179 and at its other end has a flat spring 180 and coil spring 181 connection to an arm 182 having a yoke 183 connection to the feed lift rock shaft 172. The feed dog 173 passes through suitable apertures 184 in the throat plate 84 in the usual manner and is given a four-motion movement through timed rocking of the feed rock rod 171 and feed lift rod 172. Any suitable feed dog, depending upon the material and stitch requirements, may be secured to the carrier between screws 175 in the well known manner.

Cooperating with the feed dog 173 is a presser foot 185 carried by the presser bar 75, which is tubular and operates in a bushing 75' in the head 70. The top of this presser bar carries a ball to 25 coat with a spring 186 to give pressure to the bar. This spring is under tension of the screw 187 carried by the lug 188 and may be adjusted for regulating the pressure of the spring. To prevent the rear end of the spring from shifting, it 30 is provided at its end with a pin 189 where it rests on the inner surface of the casting of the arm 43. Clamped to the presser bar 75 is a collar 190 having an extending finger 191 operating between the two guide plates 192 similarly to the 35 plates 169. This finger coats with the usual hand lifting lever 193, best seen in Fig. 5. Projecting upward from the adjustable collar 190 is an overhanging hook shaped member 194, best shown in Figs. 2 and 5. This hook shaped member 40 coats with the end of a lifting lever 195, secured to a shaft 196, to the outer end of which is secured a lever 197, see Figs. 5 and 28, connected with a chain 198 which reaches down to the usual foot lifting pedal, knee shift, or any suitable 45 means for lifting the presser foot from underneath the table, independent of the use of a hand lifting lever 193. Connected to this lever in a suitable way, is a lever 199 clamped to a rock shaft 200. This rock shaft is provided with tension release means 201 shown in Figs. 29, 30, and 50 31, and will be described.

A main connection 202, see Figs. 3 and 4, between the crank D and arm 135 secured to the feed lift rod 172 by a yoke 135' and screw 203, and having a ball and socket connection 204 to the lower end of the crank arm 114. Thus each time the crank D is given one complete turn the lower end of the arm 182, see Fig. 5, is oscillated a predetermined extent and the spring 180 at the end thereof lifts the feed dog 173 from a position below the throat plate 84 to a position level with the top thereof or slightly above it to grip the materials between it and the presser foot 185.

Operation and adjustment of the feed rocker rod 171, which controls the extent of feed, is accomplished in an advantageous manner with a novel adjusting mechanism 205 provided by the present invention. This mechanism is best illustrated in Fig. 7 through 10 and comprises an arm 70 206 secured to the trunk end of the operating rod 171 and having a link 207 connection through pivot studs 208 and 131 to a crank arm 209 having a socket connection 120 to the crank E of the main drive shaft 110. As may best be seen in 75 Fig. 7, the crank arm 209 is moved pivotally about

a bearing block 210 having a pivot pin connection 211 with a sliding finger 212 so that as the top end of the crank arm 209 is driven by the crank E in a direction to the left of the vertical centerline of the drive shaft 110, the upper end 5 of the crank arm 209 is moved to the left above the pivot pin 211 and the lower end thereof moves to the right of the centerline and simultaneously pulls the link 207 and arm 206 to the right as viewed therein in order to move the rocker rod 10 171 in a clockwise direction, and vice versa when the main drive shaft 110 moves the top end of the crank arm 209 to the right of the vertical centerline.

The bearing or pivot block 210 is movable vertically in a channel 213, formed by a notch 213' and cover plate 214, the latter being held in place by suitable bolts 215, and is moved vertically in the channel by the sliding finger 212 into any desired station. A sleeve 216, secured in lugs 217 15 and 218 integral with the side wall 54 of the trunk 41, is provided with a hollow chamber 219 to accommodate a feed or adjusting screw 220 supported in bearing sleeves 221 and 222 at the lower end with a special bearing sleeve 223 located in 20 an upper lug 224 with a set-screw 225. A pair of thrust collars 226, secured to the adjusting screw 220 with set screws 227 at opposite ends of the upper bearing 223 permits rotation of the screw and at the same time prevents axial movement thereof.

The upper end of the adjusting screw is provided with a slotted head 228 adapted to accommodate a key 229, the latter being removable by the proprietor so that the stitches per inch cannot be varied by the operator in order to make a coarser stitch and quicker output to increase his or her pay. More intricate key shapes may be provided for the same purpose. Near the lower end of the sleeve there is provided a cut-out 230 35 40 adapted to clear a feed nut 231 secured to the sliding finger 212 as by pins 232 and adapted to mesh with the adjusting screw 220 in order to move the finger 212 and pivot block 210 downwardly when rotated in one direction and to move these parts upwardly when rotated in the other direction. When the screw and feed nut are adjusted to locate and support the block in the upper position in the chamber 41' the lower end of the crank arm 209 is given a considerable oscillating movement, thereby imparting a large extent of rocking movement to the associated rocker rod 171 and considerable feeding movement to the feed dog 173 to form 8 or 10 stitches per inch. However, when the parts are adjusted so that the block is in the lowered position relative to the chamber, the lower end of the crank arm is given the relatively smaller oscillating movement so that a proportionally smaller rocking movement is given to the rocker rod and the associated feed dog to form fine stitch spacing, for example 18 or 20 stitches per inch.

Thus, the present invention provides a smooth, efficient and adjustable feeding mechanism for imparting a four motion movement in general in a direction transversely of the lower arm 45 and work support 85 from a main drive shaft 110 which is located midway in the trunk and parallel with main operating rods.

A novel gauge 233 is provided to clearly indicate to the operator at all times the extent of feed and the exact number of stitches per inch formed by the various adjustments. This gauge comprises a pointer 234 in the form of an L shaped strip attached to the feed nut 231 portion of the 70

sliding finger 212 by a screw 235 with a pointer 236 thereof adjacent a transparent plate, as may best be seen in Figs. 7 and 10, in the front wall 51 of the trunk 41. When it is desired to form 5 ten stitches per inch, the key 229 is turned until the pointer aligns with the numeral and line ten of a scale 66' on the transparent plate, and when it is desired to form twenty stitches per inch, the adjusting screw is turned through by the key until 10 the pointer is aligned with the numeral and line twenty on the scale 66'. Thus, guess work is entirely eliminated and a positive indication is given to the operator and proprietor relative to the setting of the stitch for various types of work. 15 Details of the feeding mechanism and gauge just described form the subject matter of a divisional application Serial No. 747,871 filed October 11, 1934.

Transverse type looper

20 In Figs. 2 through 6 and 15 through 18 particularly, the transverse looper type mechanism is illustrated. This is a particularly novel feature of the present improved sewing machine, resulting in a smooth control and operation of the looper in which the parts may be easily and quickly adjusted and advantageously placed for interchangeability and repair. As shown in Figs. 2, 15 and 16 particularly, the looper mechanism 25 46 includes a looper carrier 237 having a pivot connection 238 on a stud 239 projecting from a collar 240 and held to the latter with a nut 241 and washer 242. The washer sets against the end of a bearing sleeve 243 in order to prevent the carrier from sliding off the stud and at the same time permitting it to be moved pivotally thereon.

40 The looper carrier 237 is provided with a hole 244 adapted to receive a looper 89 having a thread carrying and needle hook engaging blade 45 89' held therein by a screw 245. Various types and shapes of loopers, depending upon the stitch formation desired, may be supported in the one carrier 237 in this manner.

45 The collar 240 is rotatable on an upper rod 246, the latter being supported for reciprocatory movement in bearings 247 and 248 in the trunk 41 and bearings 249 and 250 in the lower arm 45, and is axially movable on the rod, too, but is held against axial movement by thrust collars 50 251 and 252 after the looper 89 is properly located with respect to the needle 95. Spacing between the collars 251 and 252 is just enough to prevent adverse axial movement of the collar 240 55 on the rocker rod 246, yet sufficient to permit a free rotary and rocking type of movement on the rod.

60 In order to move the looper 89 relative to the needle 95, viz., to the right of the needle as viewed in Fig. 15 and thence as it moves from the retracted position shown in Fig. 16 to the advanced position shown by dot-and-dash lines F in the same figure, thence to the left or rear of the needle as shown by dot-and-dash lines G in Fig. 65 15 as it moves from the advanced position to the retracted position again, all in an elliptical path in the usual and well known manner to form a Federal Standard Stitch Style 401, the lower end of the looper carrier is provided with a connection 253 to the lower rocker rod 254. This connection 70 comprises a ball 255 having a sliding connection with a stud 256 secured to the rocker rod with a nut 257 and a ball socket 258 including an inner cap 260, and outer cap 261 connected together with studs 262 and the cap 260 being pro-

vided with an integral or an attached pivot stud 263 passing through a suitable bearing 263' in the lower end of the looper carrier 237, the latter being held thereon by a washer 264 and nut 265.

5 In order to move both the upper and lower rods 246 and 254 respectively and thereby impart four motion or elliptical travel to the looper 89, as is best shown in Figs. 2 and 15 through 18, the present invention provides driving connections 266 and 267, see Figs. 17 and 18. The connection 266 for the upper rod 246 including the crank arm 112 having a ball and socket connection 117 with the crank B on the main drive shaft and with a ball and socket connection 128 to a bell crank 133 pivotally mounted on a cross shaft 268 between a lug 269 and a thrust collar 270 as shown in Fig. 4, the bell crank 133 having a connection 271 with the upper rod 246 through a ball 272 and socket 273 as illustrated 20 most clearly in Figs. 17 and 18, the ball 272 being slidable on a stud 274 secured to the upper rod 246 with a nut 275 and the socket 273 being of a two piece cap type with holding screws 276, all being similar to the connection 253 at the 25 lower end of the looper carrier 237 shown in Figs. 15 and 16.

The main connection 267 for the lower rocker rod 254 includes the crank arm 113 having the ball and socket connection 118 with the crank 30 "C" on the main drive shaft 110 and having a ball and socket connection 129 to the front end of the arm 134 having an integral yoke 278 and screw 279 for securing it to the lower rocker rod.

35 Reciprocation of the upper rod 246 moves the looper 89 from the solid line to the dot-and-dash line position and vice versa, shown in Fig. 16, and rocking movement of the lower rod 254 moves the looper from solid line to the dot-and-dash line position shown in Fig. 15, all in timed relation with reciprocation of the needle 95.

40 Various adjustments are provided so that the position of the looper 89 relative to the needle 95, and its travel with respect thereto may be adjusted critically with comparative ease. The 45 looper may be moved so that any desired clearance is obtained between the needle and the looper when it is in the retracted position shown in Fig. 16 by sliding the carrier collar 240 and the thrust collars 251 and 252 into the desired 50 station on the reciprocating rod 246. Also the speed at which the looper approaches and leaves the needle may be adjusted by shortening or lengthening a screw 122 and lock nut 123 connection to a sleeve 121 portion of the socket 124. Thus, as the arm 280 of the bell crank 133 is 55 high at the time the crank arm 112 begins to move the bell crank in a clockwise direction, fast travel will be imparted to the looper in its initial travel toward the needle. Similarly, if connection 266 is long so that the arm 280 is on a substantially horizontal plane when the crank is first moved in its clockwise circle, the looper will be given a slow initial movement toward the needle.

60 Similar adjustments are provided for the lower 65 rocker rod 254 in order to properly adjust and cove the needle avoiding movement of the looper. The crank arm 113 is provided with screw 122 and lock nut 123 connections to threaded sleeves 70 121 in order to have the arm 134 on a higher than horizontal plane in order to impart a fast initial movement of the looper toward the rear of the needle, or is moved into a substantially horizontal plane in order to have a comparatively 75

slow initial movement. Ordinarily however, the adjustment is such that the arm 134 is moved a substantially equal extent both below and above the horizontal plane in order to have the looper travel in a substantially even timed elliptical path.

The lower rocker rod 254 is held in desired position lengthwise of the bed by collars 281 and 282 engaging bearings 283 and 284. The upper rod 10 246, however, is not held against endwise movement since it must be reciprocated in the bearings 247—250 in order to impart rocker movement to the looper carrier 237.

Since there is only a comparatively short crank arm connection between the cranks B and C and the upper rod 246 and lower rod 254, very little inertia is developed so that the parts may be operated at a very high speed. This operating advantage is also enhanced by having the main drive shaft parallel the upper rod and lower rocking rod since a comparatively straight connection 266 is provided between the crank B on the main drive shaft 110 and the bell crank connection 128 to the upper rod 246, and a similar comparatively straight main connection 267 is provided between the lower rocker rod 254 and the main drive shaft.

Multiple transverse loopers

The novel looper mechanism provided by the present invention is also especially advantageous for multiple stitching effects. Two such possibilities are illustrated in Figs. 23 through 25 and 27. In Fig. 23 the needle bar 14 is shown with a needle chuck 164a supporting two needles 95 in spaced relation, held in place by screws 285 and preferably on a longitudinal plane relative to the cloth plate 85, while the upper rod is provided with either a pair of collars 240 or a single double collar 240' as illustrated, with two pivot studs 238 supporting two carriers 237 between the thrust collars 251 and 252 on the upper rod 246 while the lower ends of the looper carriers are, through a pair of connections 253, brought into operative association with the lower rocker rod 254.

Adjustment and operation of this multiple stitching set-up is the same as with the single needle and single looper type of set-up hereinbefore described. Of course the spacing between individual needles or lines of stitching in this multiple set-up may be arranged to meet individual requirements.

The lower rocker rod 254 may be provided with a plurality of holes 256' in predetermined locations in order to facilitate adding connections thereto as it is desired to change from a single to a multiple looper arrangement in the field, and similarly the collars 240 may be made of short length between the spacing collars 251 and 252 so that two or three may be placed on the rod 246 between the walls 80 and 81 and so that they are shiftable axially thereof and held in any desired axial station thereon by the thrust collars. Also, the walls 80 and 81 may be spaced wider apart when the frame 40 is initially cast so that more loopers or wider spacing thereof may be accomplished. Thus it is not necessary to remove or partially remove the upper rod 246 or the lower rod when it is desired to change from a single to a multiple needle set-up or vice versa. In Figs. 24 and 25 there is illustrated a staggered type of multiple needle and stitching set-up including a chuck 164b secured to the end of the needle bar 14, and holding two needles 95 therein with screws 285. A suitable mating presser foot 185 and throat plate 84 are provided to properly clear the

same. A modified form of looper carrier 237' with two staggered holes 244' is provided to support two loopers 89 in proper spaced relation to the staggered needles. This modified form of carrier may replace a regular single looper carrier 237 shown in Figs. 15 and 16 by merely removing the nuts 241 and 263 and washers 242 and 263' respectively, removing the carrier 237 and replacing it with the modified carrier 237', then replacing the nuts and washers. Adjustment and operation of this form of set-up is very much the same as with the single needle and single looper type of set-up already described. With it, however, it is possible to form two lines of stitching much closer together than with the multiple set-up illustrated and described in connection with Fig. 23.

Fig. 27 illustrates a double needle and single looper type set-up for forming two simple and ornamental lines of stitching on materials during a single passage thereof on the sewing machine. For the purpose of illustration, a chuck 164c with multiple needles 95 of one spacing is shown, although other narrower or wider spacing may be provided and the standard single looper carrier 237 and looper 89 is shown cooperating therewith. Any number of commercially desirable combinations of looper and needle arrangements may be obtained with this type of mechanism; e. g. three, four, or even six needles and loopers.

Longitudinal type looper

Figs. 1, 11, and 19 through 22 clearly illustrate the advantageous mechanism 14a provided by the present invention for forming a line of stitching with a so-called looper-in-line type of feed or longitudinal type looper.

At this point it should be noted that the same rod 246 which is reciprocated to impart a rocking movement to the transverse looper carrier 237 is given both a reciprocating and rocking movement to impart both rocking and needle avoiding movement to a longitudinal type looper carrier 287.

When the machine is assembled for use as a longitudinal looper type machine, the upper rod 246 is provided with the looper carrier 287 connected to the rod by a yoke 290 and screw 291, and the looper 89' is held in a socket 288 by a screw 289. The looper carrier 287 is mounted lengthwise on the rod 246 so that it will travel from the position shown in full lines to the dot-and-dash position H in Fig. 20 relative to the needle 95 as the rod 246 is reciprocated a limited extent and is located accurately on the rod so that it is substantially in the inoperative position shown in Fig. 19 when the rod 246 is moved the full extent in counter-clockwise direction as viewed in the same figure, and so that it moves the operative position shown by dot-and-dash lines I when the rod is rocked the full extent in a clockwise direction.

Reciprocatory and rocking movement is imparted to the one upper rod 246 by the cranks B and C on the main drive shaft 110 which are used to impart reciprocatory and rocking movements to the upper and lower rods 246 and 254 respectively of the transverse looper type mechanism already described. Thus the same upper rod 246, the same driving cranks B and C, and the same main drive shaft 110 are used for both the transverse and longitudinal type mechanism. The same crank arm 112 may be used to impart reciprocatory movement to the upper rod 246 but in the present instance a modified form of

bell crank 133' is provided. This modified crank is, however, pivotally mounted on the cross rod 268 and has a ball and socket connection 128 to the crank arm 112. The main point of difference 5 being in the provision of a U shape yoke 293 straddling the upper rod with ball sections 293' between thrust collars 294 and 295 adapted to push the rod to the right and to the left as viewed in Fig. 21 when the crank B and associated crank 10 arm 112 moves up and down respectively.

This same modified form of bell crank 133' may be used equally well to reciprocate the upper rod in place of the bell crank 133 having a ball and socket final connection to the rod 212 illustrated 15 and described relative to the transverse looper type mechanism. Rocking movement of the rod 246, which moves the looper carrier 287 from the inoperative full line position shown in Fig. 19 to the dot-and-dash operative position shown 20 therein, is accomplished through a crank arm 113' having a ball and socket connection 118 with the crank "C" and having lower ball and socket connection 296 to an arm 134' locked on the upper rod 246 by a yoke 291 and screws 298. 25

Minor adjustments for controlling the speed of approach and travel of the looper carrier 287 in its rocking movement and needle avoiding movement is accomplished by the thread 122, lock 30 nut 123, and threaded sleeve 121 connections on the ends of crank arms 112 and 113' in substantially the same manner as pointed out in connection with transverse looper mechanism already described.

35 This simple, direct, and short length crank arm drive for the longitudinal type looper develops but little inertia and makes for a very high speed type of a sewing machine. Also it enables the cutting down the cross section size of the lower arm 45, if it is desired, to do only small cylindrical work on the machine with only a longitudinal type looper.

Although but a single needle 95 and single longitudinal looper carrier 287 is shown in Figs. 45 11, 19, and 20, a plurality may be provided equally well as illustrated in Fig. 26 around a double needle chuck 164d which is provided to hold a plurality of needles 95 with screws 285 and a pair of looper carriers 287 well secured to the rod 246 by tightening screws 291 in desired lengthwise relation on the rod relative to the pair of needles. Three, four, or more needles and loopers 287 may be provided for forming 3, 4, or more lines of stitching. Of course the usual 55 throat plate and feed dog changes are made in the conventional manner when changing from a single to any multiple needle arrangement.

This description in connection with Fig. 26 is given to illustrate the adaptability of the present invention to the placement of any desired 60 number of looper carriers 287 upon the rod 246 between the walls 80 and 81, which may be provided with loopers 89 locked in the proper operating position with screws 291 when it is desired 65 to have multiple needle set-up. This may be done with facility since the throat plate 84 may be removed without removing the cloth plate 85 and because of the notch 78' overlying the front wall 78 between the walls 80 and 81.

70 Loop spreader

A novel loop spreader mechanism 106 is illustrated in Figs. 1, 12, 13, 14, and 14a. Secured to the upper shaft 246 is a crank arm 300 carrying a ball stud 301 operating in one end of the

connection 302. The other end of the connection operates on ball stud 303 carried by an arm 304, of the bell crank 305, which operates on a fixed shaft 306 secured in the bearings 307 and 308. These bearings are provided with adjustable 5 bushings 309, so that lateral adjustment of the bell crank 305 may be had and also any movement of the bell crank 305 is under the control of these laterally adjustable bushings. The bell crank 305 has an upwardly projecting arm 310 to which is pivotally connected on a pin 311, a link 312, having a pivot pin connection 313 to a downwardly projecting lug 314 formed as part 10 of the loop spreader slide 106.

This loop spreader slide 106' operates in the 15 channel 107 on the under side of the throat plate 84 so as to properly be guided thereby, its location being in advance of the needles 95. This slide is provided with a thread engaging hook 108 when the machine is used for making stitch 20 formation Federal Standard Stitch Type No. 401; or more hooks 108, as shown by dot-and-dash lines in Fig. 14, if the machine is arranged for making ornamental stitches, in which case the loop spreader may serve two needles, passing 25 from one to the other, for instance as shown and described in Patent 1,961,950 of June 5, 1934, to J. P. Weis et al., or as a matter of fact, the spreader may be arranged to serve three or more needles as the case may be, for making 30 wide ornamental stitches the movement given to the spreader bar would correspond with the spacing of the needles with which the spreader hook 108 would cooperate. This arrangement of parts is simple in construction and positive in action. 35 The throat plate 84 forms the principal guide and bearing for the slide while the adaptor plate 87 upon which the throat plate is supported holds the slide 106' in channel 107 and permits endwise movement of the loop spreader under the 40 action of its driving mechanism 106 without side or up and down play.

Combined transverse and longitudinal looper

Figs. 32 through 39 show forms of the present 45 invention in which one assembly of the main driving mechanism in the trunk 41 serves equally well to operate both the transverse and longitudinal type loopers in the lower arm 45, and in which little or no replacement of parts is necessary. This represents a very advantageous 50 structure since even a comparatively unskilled operator may make the change over from one type looper to the other, and because it saves the expense of separate machines. The main 55 driving mechanism for this combination looper in the trunk 41 is substantially the same as that just described in connection with the longitudinal looper mechanism 74a to impart both reciprocating and rocking movement to the upper 60 rod 246. The only points of difference are that a connection 315 is provided between the arm 134' and the lower rocking rod 254 so that the latter will be rocked coordinately with the upper rod 246, and a connection 411 which reciprocates 65 the lower rod 254. The connection 315 comprises an arm 316 projecting from the arm 134' having a sliding pin connection 317 to links 318, the lower ends of which are provided with a stud connection 319 on an arm 320 secured by a yoke 70 321 to the lower rod 254 by screw 322.

A combination looper mechanism 74c is provided to cooperate with the needle 95 either transversely or longitudinally relative to the line of stitching. Fig. 32 discloses the transverse 75

looper set-up. It comprises a looper carrier 323 pivotally mounted on stud 324 to a collar 325 on the rod 246. This collar is held against axial movement and for rocking movement between 5 thrust collars 326 and 327 held on the rod by screws 328. The looper carrier 323 is provided with a yoke 329 fitting snugly over an eccentric 330 portion of a collar 331 secured to the lower shaft by screws 332.

10 The eccentric 330 is shaped to impart the proper extent of needle avoiding movement to a looper 333 secured by a screw 289 to a block 412 having a key and slot connection 413 to the carrier 323 to which it is secured with a holding 15 screw 414, such movement being imparted by the lower rod 254 as it is rocked by the driving connection 315, similar to the movement illustrated and described relative to the connection 253 in Figs. 15 and 16, hereinbefore.

20 Rocking movement of the looper carrier 323 is accomplished through the provision of ball sections 334 on the yoke 329 riding between lugs 335 on the collar 331 while being reciprocated by the collar 325 carried on the upper reciprocating 25 rod 246. Reciprocation of the upper rod alone and location of pivots 324 and 334 may be proportioned to alone give the desired extent of 30 looper rocking movement. However, in order to provide an evenly proportioned operating travel and even distribution of mass and inertia relative to pivots, the bell crank connection 293 of Fig. 21 or connection 271 of Fig. 17 to the upper rod 246 is replaced with the modified connection 411 in the form of a bell crank 415 on the rod 268 35 having a pin connection 416 to a lever 417 and ball connections 418 and 419 between the collars 420 and 421 to the upper and lower rods 246 and 254 respectively. Collars 281 and 282 are loosened to allow rod 254 to reciprocate. This 40 lever 417 is pivotally mounted on a stud 422 secured to a wall projection 423 intermediate the two rods as may best be seen in Figs. 34 and 36. As the bell crank 415 is rocked by the crank arm 412, the interconnected lever 417 moves the ball 45 connections 418 and 419 and associated rods in opposed directions to impart a considerable two-way movement to the looper 333 as the bell crank 415 is rocked. With this connection a considerable 50 rocking movement is imparted to the looper 333 even though the upper rod 246 is given but slight reciprocating movement. Reciprocation of the rods 246 and 254 and location of the various 55 pivots and the driving mechanism for the looper are proportioned to give the desired extent of rocking movement to the looper 333.

To change from the transverse looper of Fig. 32 to the longitudinal looper of Fig. 33 the looper block 412 is replaced with a looper block 424 secured to the looper carrier with the screw 414 60 and the eccentric collar 330 is moved into the spread position indicated by dot-and-dash lines. Various looper blocks may be secured to the one looper carrier in this manner; for example, a multiple looper block 424' as indicated by dot-and-dash lines. Also, the collar 325 is secured 65 to the rod 246 with screws 328' so that the carrier 323 rocks with the upper rod 246 and is held on the stud 324 by passing a screw 425 through a hole 426 into the collar and carrier as 70 shown in Fig. 37. Thus, the looper is rocked longitudinally and is given needle avoiding movement coordinately with the rocking and reciprocating movements respectively of the upper rod 246 alone.

Figs. 38 and 39 are similar to Figs. 32 and 33

but show a slightly modified looper carrier 323' having a low position on the stud 324 of the collar 325 to serve as a transverse looper and a high position connected to the same stud through a secondary hole 331 with a lug 339 entering a slot 5 340 in the collar 327 to serve as a longitudinal looper like the form shown in Fig. 33. With all the above forms of combination transverse and longitudinal type loopers, no changes need be made to the main driving parts in the chamber 10 and none of the rods need be withdrawn from bearings to change from one type looper to another.

Thread handling and tensioning

15 The tension release mechanism 201 is best seen in Figs. 28-31. It comprises a hollow shaft 200 provided with vent holes 200' passing through the side walls 51 and 52 of the trunk 41 as shown in Figs. 28 and 29. The hollow shaft permits air to 20 enter and the vent holes permit such air to pass into and out of the trunk chamber 41 containing the lubricant 63 and the rapidly moving parts. The vent holes may be placed crosswise and also vertical as the case may be. The passage of air 25 into and out of the oil chamber aids circulation, assists in the control of the temperature of the lubricant and also prevents the escape of any finely separated particles of lubricant in the form 30 of mist.

This shaft 200 rocks in the bearings 350 and 351 when the presser foot lifting parts are actuated by means of the chain 198 attached to the lever 197. Rocking of the shaft causes the flange 352, which is provided with a slot 353 in which 35 operates a pin 354 on a slide bar 355, to shift. This slide bar is provided with cam shape notches 356, one for each tension 357, and operates sliding pins 358 one end of which rests in the bottom of the notches and the other end, against 40 the small central cross webs of tension plates 359. These tension plates take the pressure of conical springs 360 that are carried by tension posts 361, the tension of which is regulated by nuts 362. The sewing thread 363 received from any 45 suitable supply and supports passes between the discs 359 and 359' and the operation is such that when the machine is sewing normally the pins 358 have slight end play so that the tension discs 359 transfer the pressure of the spring 360 on the 50 sewing thread 363.

When the presser foot 185 is lifted by the lever 197 an associated stud 199' moves the lever 199 and rocks the shaft 200 in the bearings 350 and 351, to shift the slide 355 in a channel 355', actuating the pins 358 to open the tension disc 359 relative to the fixed disc 359' for free passage 55 of the thread therebetween. The tension mechanism 201 is provided with projecting ears 365 carrying eyelet guides 366 to control the thread 60 as it passes part way around the tension post 361. The mounting of the tensions 357 and the complete mechanisms 201 described consist of a flat plate 367, secured to a boss 368 provided therefor on the front face of the machine trunk 41 with 65 screws 369. The slide bar 355 operates in a channel 355' of the plate 367. It will be understood that only one tension 357 will be used when one needle and one thread is required, and that any number of tensions may be provided for and used 70 in multiple needle stitching, all of which will be released at the same time with the lifting of the presser foot, 185, through manipulation of the lever 197.

Needle sewing threads 363 coming from any 75

usual supply pass through the guide eyelets 366 on each side of the tensions 357, then through eyelet guide 370 and 371, onto a control eyelet 373 of a thread control lever 374, thence to another stationary eyelet 372, and thence through the eyelet 167 carried by the needle bar 14 in its reciprocating movement. The threads pass from the eyelet 167 carried by the needle bar 14 directly to the needle 95. To give movement to the control eyelet 373, it is adjustably secured with a screw 371 to a rock shaft 378, which operates in a suitable bearing in the upper arm 43, see Figs. 2 and 28. The opposite end of this rock shaft carries a fork 379 with a rigid arm 380 and a flexible spring arm 381 which straddle a stud and roller 383 carried by a projecting arm of the presser foot lifting collar 190. This collar may be adjusted on the presser bar 75 to change the position of eyelet 373 or the forked member 379 20 may be adjusted on the shaft 378 with respect to eyelets 371 and 372, to act properly on the threads according to the character of work, variations in thickness, crossing of seams, etc. This arrangement of thread control is provided 25 for the proper setting of the stitches according to the thickness of work and automatically regulates the amount of thread given to the stitch while sewing over uneven portions of the work.

The conduct and control of the looper threads 385 from any suitable supply is accomplished by leading the threads in a suitable manner through an opening 386, see Figs. 2 and 4, directly to an eyelet guide 387, then to an eyelet guide 388, around any well known or usual tensions, directly to eyelet guide 390, thence to eyelet guide 391 which may be adjustable in any suitable manner, in a vertical as well as lateral position with respect to the looper or loopers 89 for proper control of the thread and setting of the stitch. Any number of threads can be handled in this manner for multiple row stitching.

The threads of needle and loopers described mainly make the well known Federal Standard 45 Stitch Type 401. Multiple rows of stitches are made by the mechanism shown and described. The production of ornamental and cross stitches is also made possible by simple adjustments, by changes of a few parts, or the addition of 50 simple parts, all as hereinbefore described.

Lubrication

In order to properly lubricate all the working parts a geared pump 404 is provided. As 55 may best be seen in Figs. 1, 2, 4, and 6, this pump is driven by a flexible belt 394 operating in a groove 395 of the main pulley 140 engaging a pump wheel 396 to draw lubricant through the port 397, see Fig. 6, from the reservoir, 60 thence up an oil lead pipe 398 to discharge it against the transparent plate 65 carried in the cover plate 59. The oil drops on to a fine wire mesh screen 399, which is held in a pan 400 contained in the opening of the top of the machine. The underside of the cover plate 59 is 65 provided with suitable drip lips 401, see Fig. 2, to direct oil to various parts, for example, to the tubular shaft 71 for operating the needles 95 conveying lubricant to the main bearings 70 152 and 153 thereof and to the needle bar and presser bar parts to adequately lubricate them without objectionable surplus which would be damaging to the materials being stitched.

One or more pipe leads 402, as shown in Fig. 75 2 may be provided to conduct oil to each crank

A through E and associated parts. Preferably, however, a single pipe 403 is provided as shown in Fig. 1 to conduct lubricant to a distributing pan 405 adapted to deliver and direct oil to various rapidly moving parts through spouts 406, 5 so that each time the machine is stopped surplus lubricant will be collected by this member 405 and delivered to the parts for quite some time even while the parts are without movement.

The arrangement of the parts is such as to 10 provide inlets and outlets to the bearings, to permit constant circulation of lubricant between all wearing surfaces, to adequately wash any foreign matter or particles that are constantly wearing from the bearings away from the frictional surfaces as quickly as possible, and to thereby prevent such particles from causing damage. It has been proven that through this means of constant flow of lubricant between 15 wearing surfaces, the amount of wear, over long 20 periods of time and even at the high speeds, is thereby reduced to a minimum, which is effective in prolonging the life of the machine, eliminating replacements and down time for repairs, so that the machine is more productive. 25

The present lubricating system, the main driving mechanism 42 and the main driving connections 42' provided by the present invention in the one enclosed chamber 41', are particularly advantageous for it enables the oil to drop by 30 gravity through succeeding steps onto the needle driving mechanism 71, thence onto the main driving mechanism 42, thence onto the feed mechanism 47 and looper mechanism 74; in addition, through the closed chamber and high 35 speed moving parts therein, provides a spray method of lubrication. Also the crank arms 111 through 115 are hollow with coextensive holes passing through the attached connections to the associated bearings. Further, oil passes 40 from the chamber 41' into the various rods extending lengthwise of the machine by capillary principle as indicated at 407 in Fig. 1 through 45 holes in the bearing and side wall of the rods.

The oil is indicated in the large reservoir 45 formed by the bottom of the trunk 41' by the transparent plate 66 which is provided with an oil level indicating point 408, see Figs. 6 and 10, so that the operator may know at all times by a mere glance at this transparent plate if the 50 oil is of sufficient quantity, and will be apprised if the pump 404 is working by a glance at the transparent plate 65 at the top of the machine against which the oil is forced by the pump. Thus, one is constantly aware of proper lubrication for the mechanism of the entire machine. Oil can be admitted by removing the top plate 55 59, or by any suitable screw plug at the top of the machine, and may be withdrawn by opening the spigot 67 at the bottom. 60

The lubricating system is much more completely illustrated and described, and is separately claimed, in a divisional application Serial No. 755,372, filed November 30, 1934.

Operation

Any usual prime mover, connected to the pulley 140 and intermittently started by any of the usual sewing machine clutch mechanisms, may be used to start and stop the main driving 70 mechanism 42 at will.

The machine is threaded through the various eyelets and tensions with needle threads 363, one or more according to whether a single or a multiple needle set-up is required, threaded into 75

needles 95, and looper threads 88, one or more as required, are threaded into the particular looper or loopers being used, all as hereinbefore described in detail.

5 With the transverse looper type mechanism 74 shown in Figs. 2 and 15 through 18 particularly, after the needle 95 and looper 88 are properly threaded and the main driving mechanism 42 started, the looper is driven in an elliptical path relative to the needle through its novel connections with the upper rod 246 and lower rod 254, from in front of the path of needle travel to the rear thereof and for endwise movement into the path of the needle loop.

15 The cranks A through E are located on the main drive shaft 110 in relation to each other so as to actuate the needle 95, looper 88, and feed dog 173, through the driving mechanisms 44, 46, and 47 respectively in properly timed relation to each other.

20 Since the style of stitch, the relationship and use of a four motion looper and a needle in the formation thereof are now well known in the art, further detailed description, detailed illustration of the stitch in materials, or diagrammatic showing of the step-by-step relationship of the looper and needle would only add unnecessarily to the drawings and description, they have been omitted. The various operating mechanisms for imparting synchronized movement to the needle, feed, and looper instrumentalities are, however, distinctly novel and have therefore been completely described.

25 The longitudinal type looper, shown in Figs. 1 and 19 through 22 particularly, is similarly given needle avoiding and rocking (four motion) travel in timed and spaced relation with the reciprocation of the needle 95 and movement of the feed dog, but in this instance by the upper rod 248 alone being both reciprocated and rocked by the cranks B and C in timed relation with the needle 95 and feed dog 173 through main crank arms 112 and 113', as hereinbefore described in detail.

30 Operation of the combination transverse and longitudinal looper type set-ups, shown in Figs. 32 through 35 particularly, is very much the same as for the operation of the individual transverse and longitudinal looper arrangements just described, the main point of difference residing in the modified connection 315 for rocking the lower shaft 254 and modified looper carrier 323. Thus, when the looper carrier is mounted on the pivot stud 324, and connected with both the upper and lower rods 246 and 254 as shown in Fig. 32 to function in timed and spaced relation with the travel of the needle 95 and feed dog 173 as a transverse looper, as does the transverse looper shown in Figs. 2 and 15 through 18; and, when it is mounted on the same stud 324 as shown in Fig. 33 it operates as a longitudinal looper in the same manner as does the longitudinal looper shown in Figs. 1 and 19 through 22 particularly and hereinbefore described in detail. In this combination transverse and longitudinal type looper mechanism, the change over from one to the other is easily and quickly accomplished by merely removing the throat plate 84 and changing the looper carrier from one to another station on the collar 325.

35 Operation is facilitated by the convenient centrally located main driving mechanism 42 with the hand wheel 142 located clear of the supporting table.

40 From the foregoing it will be apparent that the present invention provides an improved sewing

5 machine with a novel work support 48 construction which may be easily and quickly changed from a flat bed to a cylindrical type, and in which the cloth plates may be changed without disturbing the throat plate, or vice versa. Also, 5 that it provides a sewing machine which may be easily and quickly changed from a transverse looper to a longitudinal type sewing machine, with smooth and efficient mechanism to operate either type.

10 Improved mechanisms are also provided to control and tension the threads and particularly improved mechanisms to impart a smooth and efficient drive or operating movement to the needle and to the feed dog synchronously with the 15 looper to do high quality stitching on a high production basis. In this latter connection the invention also provides an improved needle guard and improved needle loop spreader. The improved sewing machine of the present invention 20 also provides a novel driving mechanism and an improved lubricating system, both of which insure a smooth, efficient and continuously satisfactory operation.

25 Variations and modifications may be made 25 within the scope of this invention, and portions of the improvements may be used without others.

Having thus described the invention, what is new and for which it is desired to obtain Letters Patent is:

30 1. In a sewing machine the combination of a frame with an upper and a lower arm; a main drive shaft in said frame; a needle bar in the upper arm; a rocking rod in the lower arm; a combination rocking and reciprocating rod in the 35 lower arm; a sleeve on said combination rod; an eccentric collar on the rocking rod; means adapted to operate said needle bar and said rocking and combination rods synchronously; a looper; and a looper carrier adapted to be connected to the sleeve on the combination reciprocatory and 40 rocking rod alone for two motion operation longitudinally relative to the line of feed and to be connected to the sleeve on the combination rod and to the eccentric collar on the rocking rod 45 for two motion operation transversely relative to the line of feed.

2. In a sewing machine the combination of a frame having a trunk with upper and lower arms; a main drive shaft in said frame; a needle bar in the upper arm; a looper in the lower arm; a reciprocating rod in the lower arm; a four-motion connection between said looper and said reciprocating rod; a rocker rod; a connection between the rocker rod and the looper; and means associated with the main drive shaft adapted to operate the needle bar, and to impart four-motion operation to the looper through said reciprocating and rocking rods.

3. In a sewing machine the combination of a 60 frame having a trunk with upper and lower arms; a main drive shaft in said frame; a needle bar in the upper arm; a looper in the lower arm; a reciprocating rods in the lower arm; a rocking rod in the lower arm; four-motion connections between said reciprocating rod, rocking rod, and looper; and means associated with said main drive shaft adapted to operate said needle bar, and adapted to operate the reciprocating and rocking rods to impart four-motion operation 65 to the looper in timed relation with the needle bar.

4. In a sewing machine the combination of a frame with upper and lower arms; a main drive shaft in said frame; a needle bar in the upper 75

arm; a looper in the lower arm; a reciprocating rod in said lower arm; a sleeve on said reciprocating rod engaging the looper intermediate its length; a rocker rod in the lower arm; a connection between said rocker rod and the lower end of the looper; and means associated with the main drive shaft adapted to operate the needle bar, reciprocating rod, and rocker rod in timed relation to impart a four-motion travel to said looper.

5. In a sewing machine the combination of a frame having a trunk with upper and lower arms; a main drive shaft rotatably supported in the trunk; a needle bar in the upper arm; a looper in the lower arm; a reciprocating rod in the lower arm; a sleeve carried by said reciprocating rod; a pivot on said sleeve, providing a pivotal mount for the looper for arcuate movement thereof transverse to the direction of the line of stitching, 15 while the sleeve permits movement of the looper longitudinally relative to the line of stitching; a rocking rod in the lower arm; a connection between the rocking rod and the looper adapted to rock the looper and sleeve about the reciprocating 20 rod longitudinally relative to the line of stitching; and driving connections associated with the main drive shaft for operating the needle bar and adapted to operate the reciprocating and rocking rods to impart four-motion travel to the looper 25 in timed relation to operation of the needle bar.

6. In a sewing machine the combination of a frame having a trunk with upper and lower arms; a feeding mechanism having a feeding movement transversely of the lower arm; a needle operating 30 mechanism; a looper mechanism; a main drive shaft in the trunk substantially midway of and parallel with the upper and lower arms; and means for operating the feeding mechanism, needle operating mechanism and the looper mechanism synchronously, including crank arms connected from said main drive shaft to each of said mechanisms.

7. In a sewing machine the combination of a frame having a trunk with upper and lower arms; a feeding mechanism having a feeding movement 35 transversely of the lower arm; a needle operating mechanism; a combination reciprocating and rocking rod; a bell crank associated with said combination rod; a looper connected to said combination rod; a main drive shaft in the trunk, substantially midway of and parallel with the upper and lower arms; and means for operating the feeding mechanism, needle operating mechanism and said looper synchronously, including 40 crank arms connected from the main drive shaft to the feeding mechanism, needle operating mechanism, bell crank and combination rod.

8. In a sewing machine the combination of a frame having a trunk with upper and lower arms; 45 a feeding mechanism having a feeding movement transversely of the lower arm; a needle operating mechanism; a reciprocating rod; a rocking rod; a looper associated with said reciprocating and rocking rods; a main drive shaft in the trunk, substantially midway of and parallel with the upper and lower arms; and means for operating said feeding mechanism, needle operating mechanism, and looper synchronously, including crank arms connected from the main drive shaft to said 55 feeding mechanism, needle operating mechanism, reciprocating rod, and rocking rod.

9. In a sewing machine the combination of a frame having a trunk with upper and lower arms; a feeding mechanism having a feeding movement 60 transversely of the lower arm; a needle operating

mechanism; a reciprocating rod; a bell crank associated with said reciprocating rod; a rocking rod; a looper associated with said reciprocating and rocking rods; a main drive shaft in the trunk, substantially midway of and parallel with the upper and lower arms; and means for operating said feeding mechanism, needle operating mechanism and looper synchronously, including crank arms connected from the main drive shaft to said feeding mechanism, needle operating mechanism, 10 bell crank and rocking rod.

10. In a sewing machine the combination of a frame having a trunk with upper and lower arms; a feeding mechanism having a feeding movement transversely of the lower arm; a needle operating 15 mechanism; a rocking rod associated with said feeding mechanism; a looper mechanism; a main drive shaft in the trunk substantially midway of and parallel with said upper and lower arms; and means for operating the feeding, needle operating 20 and looper mechanisms synchronously, including short substantially equal length crank arms connected downwardly to said feeding and looper mechanisms and upwardly to the rocking rod of the needle operating mechanism.

25 11. In a sewing machine the combination of a frame having a trunk with upper and lower arms; a feeding mechanism having a feeding movement transversely of the lower arm; a needle operating mechanism; a rocking rod associated with said needle operating mechanism; a reciprocating rod; a rocking rod in the lower arm; a looper associated with said reciprocating and rocking rods; a main drive shaft in said trunk, substantially midway of and parallel with the upper and lower arms; and means for operating the needle operating mechanism, feeding mechanism and looper synchronously, including short substantially equal length crank arms connected from the main 30 driving shaft downwardly to said feeding mechanism and said reciprocating and rocking rods and upwardly to said rocking rod of the needle operating mechanism.

40 12. In a sewing machine the combination of a frame having a trunk with upper and lower arms; a feeding mechanism having a feeding movement transversely of the lower arm; a needle operating mechanism; a looper mechanism; a main drive shaft in said trunk, substantially midway of and parallel with the upper and lower arms; and means, including short substantially equal length crank arms connected from said main drive shaft to said looper, feeding, and needle operating mechanisms, for operating the needle operating mechanism and the feeding mechanism and to 45 synchronously impart two motion needle loop taking and shedding travel to said looper mechanism both transversely and longitudinally relative to the line of feed.

55 13. In a sewing machine the combination of a frame having a trunk with upper and lower arms; a feeding mechanism having a feeding movement transversely of the lower arm; a needle operating mechanism; a looper mechanism; a main drive shaft in said trunk, substantially midway of and parallel with the upper and lower arms; and means, including short substantially equal length crank arms connected from said main drive shaft to said looper, feeding, and needle operating mechanisms for operating the needle operating 60 mechanism and the feeding mechanism and to synchronously impart four-motion needle loop taking and shedding travel to said looper mechanism both transversely and longitudinally relative to the line of feed.

14. In a sewing machine the combination of a frame having a trunk with upper and lower arms; a needle operating mechanism; a feeding mechanism adapted to move work transversely over the lower arm; a rocker rod in said feeding mechanism; a link on said rocker rod; a looper mechanism capable of two-motion operation both transversely and longitudinally relative to the line of feed; a main drive shaft in said trunk substantially midway of and parallel with said upper and lower arms; means adapted to operate said looper, feeding, and needle operating mechanisms and said rocker rod synchronously; a crank arm in said means, connected from said main drive shaft to said link of the rocker rod; and an adjustable pivot for said crank arm adapted to vary and control the extent of rocker rod and associated feeding mechanism movement.

15. In a sewing machine the combination of a frame having a trunk with upper and lower arms; a work support; a needle loop spreader in said work support; a needle operating mechanism; a feeding mechanism adapted to move work transversely over the lower arm; a looper mechanism; a combination reciprocating and rocking rod in said looper mechanism; a main drive shaft; means adapted to operate said needle operating and feeding mechanisms and to synchronously impart four-motion travel to said looper mechanism through said combination rod; and a connection between said combination rod and said needle loop spreader adapted to operate the spreader synchronously with the needle operating mechanism.

35 16. In a sewing machine, the combination of a frame; a main drive shaft; a needle; a looper; a reciprocating rod, for the looper; a single rocker rod for the looper; a connection between the rocker rod and reciprocating rod, pivotally and movably supporting the looper for free four-way motion on the rocking rod; and means associated with the main drive shaft adapted to impart four-way motion to the looper through said reciprocating and rocking rods.

45 17. In a sewing machine the combination of a frame; a main drive shaft; a needle carrier, a looper; a reciprocating rod; a sleeve on said reciprocating rod engaging the looper intermediate its length; a rocker rod; a connection between said rocker rod and the lower end of the looper; and means associated with said main drive shaft adapted to operate the needle carrier, reciprocating rod and rocking rod in timed relation to impart four-motion travel to said looper.

55 18. In a sewing machine the combination of a frame; a main drive shaft; a needle carrier; a looper; a reciprocating rod; a sleeve on said reciprocating rod engaging the looper intermediate its length; a rocker rod; a connection between said rocker rod and the lower end of the looper; and crank connections associated with said main drive shaft adapted to operate the needle carrier, reciprocating rod and rocking rod in timed relation to impart four-motion travel to said looper.

60 19. In a sewing machine the combination of a frame with upper and lower arms; a main drive shaft in said frame; a needle bar in said upper arm; a looper carrier in said lower arm; and means associated with said main drive shaft for reciprocating the needle bar and for imparting two-motion needle loop seizing and shedding travel to said looper carrier both transversely and longitudinally relative to the line of feed,

the looper carrier being provided with means for receiving a looper which will be given its loop seizing movement in one of said carrier movements and means for receiving a looper which will be given its loop seizing movement during the other motion of the carrier.

5 20. In a sewing machine the combination of a frame having a trunk with upper and lower arms; a main drive shaft in said frame; a needle bar in the upper arm; a looper carrier in the lower arm; and means associated with said main drive shaft for operating the needle bar and for imparting four-motion operation to said looper carrier with needle loop seizing and shedding travel both transversely and longitudinally relative to the line of feed in timed relation to the operation of the needle bar, the carrier having means for receiving a looper which will be given its loop seizing movement by one of said carrier movements and means for receiving a looper which will be given its loop seizing movement during another motion of said carrier.

10 21. In a sewing machine the combination of a frame having a trunk with upper and lower arms; a main drive shaft in said frame; a needle bar in the upper arm; a looper carrier in the lower arm; a pair of rods in said lower arm; driving connections associated with said main drive shaft for operating the needle bar and for imparting reciprocating and rocking movement to said pair of rods; and connections between said looper carrier and said pair of rods for selectively effecting four-motion operation to said looper carrier with needle loop taking and shedding travel both transversely and longitudinally relative to the line of feed, in timed relation to the operation of the needle bar, the carrier having means for receiving a looper which will be given its loop seizing movement by one of said carrier movements and means for receiving a looper which will be given its loop seizing movement during another motion of the carrier.

15 35 22. In a sewing machine the combination of a frame with upper and lower arms; a main drive shaft in said frame; a needle bar in the upper arm; a looper carrier; and means associated with said main drive shaft for reciprocating the needle bar and synchronously to impart two-motion needle loop taking and shedding travel to said looper carrier both transversely and longitudinally relative to the normal line of feed, said looper carrier being provided with a plurality of means for mounting a looper which will be given its loop seizing movement in one of said carrier movements and a looper which will be given its loop seizing movement during the other motion of the carrier.

24. In a sewing machine the combination of a frame having a trunk with upper and lower arms; a needle bar in the upper arm; a looper carrier in the lower arm; a main drive shaft in the trunk; 5 means associated with said main drive shaft for operating the needle bar and for imparting four-motion needle avoiding and needle loop taking and shedding travel to said looper carrier both transversely and longitudinally relative to the 10 line of feed, the looper carrier being provided with means for receiving a looper which will be given its loop seizing movement in one of said carrier movements and means for receiving a looper which will be given its loop seizing movement 15 during the other motion of the carrier; and adjustable connections in said associated means adapted to change the speed of travel of said looper carrier relative to the needle bar.
25. In a sewing machine the combination of a 20 frame; a work support; a needle bar; a looper carrier; a needle loop spreader in the work support; and means for operating the needle bar and synchronously to impart two-motion needle loop taking and shedding travel to said loop carrier both transversely and longitudinally relative 25 to the line of feed, the looper carrier being provided with means for receiving a looper which will be given its loop seizing movement in one of said carrier movements and means for receiving a looper which will be given its loop seizing movement 30 during the other motion of the carrier.
26. In a sewing machine the combination of a frame with upper and lower arms; a main drive shaft in said frame; a needle bar in the upper 35 arm; a looper carrier in the lower arm; and means for operating the needle bar and synchronously to impart two-motion needle loop taking and shedding travel to the looper carrier both transversely and longitudinally relative to the normal 40 line of feed, the looper carrier being provided with means for receiving a looper which will be given its loop seizing movement in one of said carrier movements and means for receiving a looper which will be given its loop seizing movement 45 during the other motion of the carrier.
27. In a sewing machine the combination of a frame with upper and lower arms; a main drive shaft in said frame; a needle carrier in the upper arm; a looper in the lower arm; one rod in the 50 lower arm supporting and actuating said looper; and means associated with said main drive shaft and rod for imparting four-motion operation to the one rod for imparting needle loop taking and shedding travel to the looper longitudinally rela-

tive to the normal line of feed in timed relation with the operation of the needle carrier.

28. In a sewing machine the combination of a frame; a main drive shaft, a needle carrier; a rocking rod; a combination rocking and reciprocating rod; a sleeve on said combination rod; an eccentric means on the rocking rod; means for operating said needle carrier, rocking rod and combination rod synchronously; and a looper carrier formed to be selectively connected to the 10 sleeve alone for needle loop taking and shedding travel longitudinally relative to the normal line of feed, and to the sleeve and to the eccentric means on the rocking rod for the needle loop taking travel transversely relative to the normal 15 line of feed, the looper carrier being provided with means for receiving a looper which will be given loop seizing movement in one of said carrier movements and means for receiving a looper which will be given loop seizing movement during 20 the other motion of the carrier.

29. In a sewing machine the combination of a frame; a needle carrier; a looper carrier; two combination reciprocating and rocking rods; means for operating said needle carrier and said 25 two rods coordinately; and means associated with said two rods for supporting said looper carrier and to impart needle loop taking and shedding travel to said looper carrier transversely and longitudinally relative to the normal line of feed, 30 the looper carrier being provided with means for receiving a looper which will be given loop seizing movement in one of said carrier movements and means for receiving a looper which will be given loop seizing movement during the other motion of 35 the carrier.

30. In a sewing machine the combination of a frame; a needle carrier; two combination reciprocating and rocking rods; means for operating said 40 needle carrier and said two rods coordinately; and a looper carrier formed to be selectively associated with both of said rods for needle loop taking and shedding travel longitudinally relative to the normal line of feed, and with one of said rods for needle loop taking and shedding 45 travel transversely relative to the normal line of feed, the looper carrier being provided with means for receiving a looper which will be given loop seizing movement in one of said carrier movements and means for receiving a looper which will be given loop seizing movement during the 50 other motion of the carrier.
